CHAIN SAW GUARD

Prior chain saw guards of which I am aware have in general comprised either (1) a cloth sock which encloses the saw bar and its chain, but this allows the saw bar chain to sweat and rust, or (2) a perforated plastic cover which is rather expensive. I am also aware of the guard shown in the patent to Tyrrell, No. 3,129,721, wherein the walls of the guard converge inwardly so that they must be forcibly spread apart to fit over and snap into engagement with the saw bar.

The chain saw guard of the present invention comprises a guard member as described in the abstract (above) which has resilient legs which can be spread apart to enable the guard to fit onto the saw bar and its chain, and has stop lugs to releasably retain the guard member in place.

FIG. 1 shows in solid lines my guard mounted on a saw bar and its chain, and shows in broken lines the leg portions of the guard in spread condition for application to the saw bar and chain;

FIG. 2 is a view of the saw guard in its relaxed and undistorted condition;

FIG. 3 is a vertical section taken along line 3-3 of FIG. 2;

FIG. 4 is a view of a modified form of guard;

FIG. 5 is a fragmentary side view of another modified form of guard;

FIG. 6 is a view of the clamping band of FIG. 5; and

FIG. 7 is a fragmentary side view of a guard like that in FIGS. 1 and 2 but which is differently constructed at the curved portion of the guard.

Referring to FIGS. 1 and 2, the chain saw guard comprises a molded plastic guard member 11 of generally C-shape having elongate legs 13 and 15. The legs converge toward one another in the undistorted condition of the guard for a purpose to be described.

The guard member comprises an outer wall 17 and inwardly extending parallel side walls 19 and 21 so that the guard member is U-shaped in cross section throughout.

At the curved portion 18 of the guard member, a pair of gusset portions 18a are molded integrally with the side walls 19 and 21. A reinforcing bead 22 is formed on the inner margin of each wall and extends around the inner margin of the associated gusset.

The spacing between the side walls 19 and 21 of a leg of the guard member is substantially uniform from the outer wall 17 to the inner free margins 22a of such side walls. This spacing is slightly greater than the thickness of the saw chain 23 so that the guard will freely fit over the chain without having to spring the side walls apart.

Each of the legs 13 and 15 has a retainer or stop lug 25 formed thereon near the free end thereof. FIG. 3 shows that each lug extends across the channel provided by the associated leg, and is integrally joined to the side walls and outer wall of its leg. Each lug terminates short of the inner margins 22a of the side walls of its leg so that it can fit behind a raised portion of the chain 23 and be accommodated within one of the spaces or gaps provided by the teeth and links of the chain. Thus the lugs do not interfere with nor prohibit the chain from being covered by the side walls of the legs of the guard member 11.

The legs 13 and 15 are flexible so that they can be sprung apart from their FIG. 2 positions to their broken line positions in FIG. 1 for the purpose of disposing the lugs 25 outwardly of the chain to enable the guard member to be moved into enclosing relation with respect to the chain. Thereafter the legs are released to allow them to snap into place in clamping relation against the chain. The clamping action is achieved because the legs, when in contact with the chain, will be held outwardly of their normal undistorted FIG. 2 positions. In the event the lugs 25 do not fall into gaps in the chain, the guard member and/or chain may be shifted slightly to effect this result. The lugs can fit in the gaps provided by the chain links 29 or they can fit in the gullets 31 of the teeth 33. The lugs, when in place, prevent endwise dislodgment of the guard member from the saw bar and its chain. Thus, the guard member is releasably retained in place on the chain saw until it

is removed by springing the legs 13 and 15 apart and moving the guard member to the left, as the parts are shown in FIG. 1.

The guard member has a length slightly less than the exposed portions of the bar and chain so that the guard encloses and protects substantially the entire exposed chain portions.

FIG. 4 shows a modified form of guard wherein each leg has two retaining lugs, the leg 15a shown in FIG. 4 having lugs labeled 25a.

FIGS. 5 and 6 show a modified form of guard having legs

13b and 15b each having a cross-sectional shape the same as legs 13 and 15. Legs 13b and 15b have no retainer lugs 25 and instead each leg has a pin 41 on the outer wall thereof near the free end of the leg. An elastomer retainer band 43 shown in plan in FIG. 6 is formed with an eye 45 at each end.

The guard is applied to a saw bar and its chain. Then one eye 45 is fitted onto a pin 41. Next, the band is wrapped several times around the guard and saw bar assembly and the other eye fitted onto the other pin to hold the guard in clamping relation to the saw bar and chain.

FIG. 7 shows a guard member 51 which is formed like the guard member of FIG. 2 except that guard member 51 has no gusset portions 18a as does guard member 11.

Having described the invention in what is considered to be the preferred embodiment thereof, it is desired that it be understood that the invention is not to be limited other than by the provisions of the following claims.

I claim:

1. A guard for application to a chain saw:
said guard comprising a generally C-shaped guard member having elongate legs which have predetermined positions relative to one another in the undistorted form of said member, but which can be temporarily separated under a spreading force, and in such spread condition are urged by the stresses set up in said member to return to said predetermined positions;

said guard member being defined by an outer wall and spaced, parallel, generally inwardly extending sidewalls; the edges of said sidewalls being spaced apart a distance greater than the width of the saw chain on a saw so as to readily pass over such chain when the guard member is being applied to the saw;

said guard member being of a length just short of that of the length of the exposed portion of the saw bar to which it is to be applied;

said legs converging toward one another an extent such that the end portions of said legs are spaced from one another a distance less than the overall width of the saw bar and saw chain to which it is to be applied, so that the legs have to be sprung apart to be applied to the saw bar and saw chain, and when the spreading force is released, said legs in tending to return to said predetermined positions will contact the saw chain whereby to clampingly engage the same, whereby said guard member is retained on the saw, in a direction widthwise of the saw blade, solely by said clamping action;

said guard being retained on the saw in a direction normal to the saw blade by said side flanges which act as retainers;

each leg of said guard member having adjacent its free end and interiorly thereof a chain engaging stop lug to fit behind a raised portion of chain and retain said guard member on said saw in a direction lengthwise of the saw blade; and

said guard member being retained on the saw blade and chain solely by the combination of the clamping action of said legs, the retaining action of said sidewalls and the stopping action of said lugs.

2. A chain saw guard comprising:
a generally C-shaped guard member having elongate leg portions;
said member being defined by an outer wall and spaced, generally parallel inwardly extending sidewalls so that it is U-shaped in cross section throughout;

said member being of a length just short of that of the exposed portion of the saw bar to which it is to be applied; means to retain the guard member on a saw bar and its chain against accidental dislodgment; and

each leg having an outwardly projecting pin thereon, and a stretchable band having a length at least several times the distance between the legs and wrapable around the guard and having eyes to fit on the pin.
